ELECTRICAL DEVICE

Werner I. Staaf, Rennerdale, Pa.

Application May 29, 1944, Serial No. 537,933

2 Claims. (Cl. 200—152)

1

This invention relates to electric switches or circuit make-and-break devices, and particularly to devices of this class in which an electrical conductive fluid, typically mercury, comprises the essential circuit-controlling or current-carrying element of the device.

While mercury switches are desirable for use in many fields because of the fact that they are positive in their operation and eliminate spring contact devices and contact blades which may become worn or spread, or may otherwise become unsatisfactory, the field of use of mercury switches as constructed at the present time is relatively limited, due to the fact that the effect of gravity is principally relied upon for their operation. The more familiar types of mercury switches comprise glass tubes, mounted for tilting or turning movement, the arrangement being such that when the tube is tilted or turned in one direction, the mercury gravitates to the lower end of the tube and closes a circuit, whereas when the tube is tilted in the reverse direction, the mercury flows to the opposite end and the circuit is broken. Less common forms of mercury switches employ a reservoir and piston arrangement, wherein the movement of a plunger into the reservoir raises the height of a column of mercury to a point where the mercury contacts a circuit-closing element. When the plunger is withdrawn the column of mercury drops into circuit-interrupting position. The field in which both types of switches may be used is obviously limited, because of the effect of gravity and the effect of inertia. The tilting devices obviously may not be used in any kind of mobile equipment, because of the changes of inclination of such equipment, bouncing, sharp changes of direction, etc., and the second type of mercury switch mentioned is even less well adapted to such use.

The present invention provides a mercury switch which is of simple and rugged construction, which is positive in its operation, which is primarily not dependent upon gravity, and which eliminates delicate or elaborate pivoting or tilting suspension, and which may be mounted in various ways without resorting to elaborate specialized construction. It provides a mercury switch which can be substituted in various places for movable contact blade switches now widely used, and it may be adapted for operation by relays or other automatic actuating devices, as well as for operation by hand.

While the structure of the invention is adapted for use as electrical make-and-break and/or current conducting devices in general, it is par-

2

ticularly designed for electrical switches, and herein I shall so describe it, with the understanding that within the terms of the appended claims various devices, in which a conductive fluid forms an essential current-carrying element, are included. In the accompanying drawings:

Figure I is a view in transverse section of a switch embodying the invention;

Figure II is a view in plan of the switch;

Figure III is a view comparable with Figure I, indicating in dotted lines a push-button device that may be organized for operating the switch. Whereas in Figure I the switch is shown in circuit-closing position, in Figure II the switch is shown in circuit-interrupting position;

Figure IV is a view in plan of a certain element that is embodied in the switch structure;

Figure V is a view in cross section of a modified form of the switch of the invention; and

Figure VI is a view in plan of the modified structure of Figure V.

Referring to the drawings, the switch herein illustrated consists in a container formed of a block-like body 2 of electrical insulating or dielectric material that is shaped to provide an annular well 3 for a pool 4 of mercury or other electrical-conductive fluid. The body or block 2 is formed of porcelain, or glass, or hard rubber or pressed fibre, or the like, which is not wetted by mercury. At the center of the body 2 a conical recess 5 opens into the well 3, and the bottom of this recess is formed by the laterally extended head of a screw 6. The screw 6 provides one of two electrical contacts which are accessible to the mercury within the switch structure.

The body 2 of the switch is encased in a housing formed of a disk 7 of hard rubber or other suitable insulating material, a circumferential metal sheath 8, and a flexible metal diaphragm 9, the metal diaphragm being united (as by welding) in a liquid-tight joint 8a to the adjacent edge of the sheath 8, and the opposite edge of the sheath 8 being peripherally clinched, as at 8b, upon the edge of the disk 7. A complete enclosure of the switch structure is thus provided. As will presently appear, the metal body of the diaphragm 9 comprises the other of the two electrical contacts which are accessible to the mercury within the switch.

As exemplary of means for rigidly securing the switch in an outlet-box or other support (not shown), the insulating disk 7 is radially extended in two lugs or ears 7a, perforated for the use of screws or bolts in obvious way.

The threaded stem of the screw 6 is extended

outward through the insulating disk 7, and an electrical connector 10 is secured thereto by and between two nuts 10a, while a gasket 6a of insulating material is positioned between the head of the screw and the disk 7 to provide a tight assembly of the parts. The outer end of the connector 10 is equipped with a conventional clamping screw 14 to provide one terminal of the switch for the connection of a conductor A of an electrical circuit.

A metal band 15 is clamped in electrical union upon the metal casing of the switch by means of a screw 16, and this screw serves not only to secure the band, but additionally to provide the other terminal to which an electrical conductor B may be attached. Thus, it will be perceived that the switch may be connected in an electrical circuit A, B. Since the screw 6 and the metal diaphragm 9 severally stand in electrical communication with the switch terminals 14 and 16, it will be understood that the body of mercury within the switch is adapted to close a circuit through the conductors connected to the switch, as indicated in Figure 1.

In accordance with the invention, I provide particularly effective means within the switch structure positively to move the mercury between a position in which the circuit A, B is closed and a position in which the circuit is open. Such means advantageously consist in a device which physically displaces so much of the mercury as is necessary to achieve such effect. In this case, the device comprises a member 17 formed of insulating material and mounted for movement from the circuit-closing position shown in Figure 1 (in which the body of mercury electrically unites the screw 6 with the metal casing 8, 9 and closes the circuit) to the circuit-interrupting position shown in Figure 3 (in which the member 17 displaces the mercury to the extent necessary to form a barrier of insulation in the path of electrical communication between the switch terminals). The member 17 is here shown as a block of porcelain, or other insulating material, which like the body 2 is not wetted by the mercury. The means for supporting such block for movement between said alternate positions comprise the flexible diaphragm 9 of the switch casing.

More particularly, the block 17 is attached to a metal disk 18 formed with a castellated periphery, the attachment being effected by clinching the projecting portions of the castellated edge of the disk upon the beveled rim of the block. The metal disk 18 is secured to the center of the diaphragm 9 by means of a stud 20, and the diaphragm is adapted under stress applied to the stud to be flexed from the position in which it is shown in Figure 1 to the position shown in Figure 3. The movement of the diaphragm between such positions is a snap-action movement which shifts the mercury-displacing block 17 between its alternate circuit-controlling positions, and the design and elasticity of the diaphragm are such that the diaphragm is adapted to maintain the block 17 in either of said positions into which it is sprung.

It will be understood that, when the block 17 moves into circuit-interrupting position, it displaces the mercury between the annular seat portion 2a of the container body that encompasses the well 5, and under the elasticity of the flexed diaphragm the block is sprung into snugly seated position on said annular portion 2a. By virtue of the fact that the body 2 and the block 17 are

formed of material that is not wetted by the mercury, there is no tendency for any of the mercury to remain between or adhere to the meeting surfaces of the block and the container body.

5 Accordingly, while the recess or well 5 may contain mercury when the block 17 is seated over the mouth of the well, there is absolute electric isolation of the head of screw 6 from the metal casing of the switch; that is, the terminals of the 10 switch are isolated, with the circuit A, B open or interrupted.

In order that the block 17 shall not hamper the deflection of the diaphragm, a spacer 21 is positioned between the block and the diaphragm.

15 The stud 20 is shaped externally of the diaphragm in the form of a grooved head 20a, and this head forms a button that may be pushed or pulled by the fingers of the switch operator, to flex the diaphragm either inward or outward to shift the mercury-displacing block from one to the other of its said alternate circuit-controlling positions.

In case the switch be incorporated in a conventional wall switch (not shown) the head 20a of the stud affords means for connecting the mercury-displacing block or plunger 17 to the switch-operating mechanism of the wall switch. In Figure 3, the cover plate 22 and toggle 23 of a push-button wall switch are indicated in dotted lines, and the manner in which the toggle arm may be engaged in the groove of the head 20a to provide for push-button operation of the switch will be manifest to those skilled in the art.

It will be perceived upon consideration of the drawings that the switch structure will be operative in any position in which it may be mounted on a support, save a horizontal position in which the stud head 20a is directed downward, for with the switch in that position the mercury will lie in a pool upon the inner face of the diaphragm and will not make contact with the head of the screw 6 to complete the circuit in which the switch is connected. But, it will be understood that this circumstance imposes no serious impediment upon the utility of the switch under normal conditions of service.

Figures 5 and 6 illustrate one of the many permissible modified forms of the structure of the invention. Whereas in the device of Figures 1 to 4 the mercury-displacing block 17 comprises a plunger that is movable in a direction normal to the mouth of the recess 5 and the head of the contact screw 6 exposed therein, in the modified structure the plunger block 17c is adapted to move transversely of the mouth of the recess 5c, the container body 2c being appropriately modified in form to provide an elongate seat 2d surrounding the recess 5c and upon which the block 17c may slide. The metal casing 8c is modified in form, corresponding to the modified shape of the body or block 2c of insulating material, and such casing is shown as a metal casting rather than a shaped and welded structure of sheet metal. The 65 only other changes that may require mention for those skilled in the art are, as follows:

Since the casing 8c is formed as a casting the insulated disk 7c that forms the casing wall portion through which the contact screw 6c extends is secured in place by means of an independently formed clamping ring 8d drawn tight by means of screws 8e threaded into the body of the casting 8c. One terminal, 14c, of the switch is connected to the contact screw 6c as in the structure first described, and the other terminal,

16c, is attached to the metal casing 8c, 8d with which the pool 4c of mercury is in contact.

The means for shifting the mercury-displacing plunger between its alternate circuit-controlling positions comprise a plunger rod 24 that extends outward from the metal casing through a stuffing box 25, whereby it may be equipped with, or connected to, suitable means for effecting the switch-operating reciprocation of the rod, as desired. The attachment of the plunger rod to the block 17c is formed by a stud 20c rigid with the disk 18c that is united to the block, and this stud fits in an orifice provided in the end of the plunger rod, which is flattened at its inner end, as shown, to accommodate an orifice of the diameter of the stud. A leaf spring 26, clamped at one end between the assembled body 2c and casing 8c, bears upon the otherwise free end of the stud, and serves to hold the mercury-displacing block in snug contact with the seat 2d upon which it slides. With the parts in the positions in which they are shown in Figure 5, the block 17c manifestly electrically isolates the switch terminals 14c and 16c, whereby the circuit in which the switch is included stands open. Alternately, upon the outward movement of the plunger rod 24, the block 17c is moved to the right into a position in which the pool of mercury electrically unites the contact screw 6c with the metal casing of the switch, and thereby electrically unites the switch terminals and closes the circuit in which the switch is connected. Thus, the reciprocation of the plunger rod is adapted to shift the mercury-displacing element 17c between its alternate positions to open and close said electrical circuit.

It will be seen that both of the structures described function on the same principles of operation, and it will be understood that many variations in structure lie within the field of invention covered in the appended claims.

I claim as my invention:

1. A positive displacement mercury switch

comprising a block of dielectric material and a housing member comprised of electrical conducting material assembled with the block to form an enclosed well, a recess formed in said block of dielectric material to open into said well, a body of mercury in said well and recess, said block including a portion forming a seat that encompasses said recess, an electric contact element exposed in said recess to said body of mercury and extending outward from the block to form a circuit terminal, and a plunger of dielectric material movable in said well into and from position on said seat and adapted when positioned on said seat to provide an electric barrier between said contact and the mercury in said well in contact with the electrical conducting material of said housing.

2. The structure of the preceding claim, said housing member comprising a flexible diaphragm to which said plunger is connected for movement therewith.

WERNER I. STAAF.
